Des. 233,371
Patented Oct. 22, 1974

233,371

SUN DOME

Gregory P. Fila, Wingdale, N.Y. 12594

Filed July 28, 1972, Ser. No. 276,089

Term of patent 14 years

Int. Cl. D24—99

U.S. Cl. D83—1 C

FIG. 1

FIG. 2

FIG. 3

FIG. 4

FIG. 1 is a perspective view of a sun dome showing my new design;

FIG. 2 is a side view of the sun dome in FIG. 1 with the dome shown in closed position;

FIG. 3 is a perspective view of an alternate embodiment of a sun dome; and

FIG. 4 is a side view of the sun dome of FIG. 3 with the dome shown in a transitional position.

I claim:

The ornamental design for a sun dome, substantially as shown and described.
